DESIGN FOR A TOY VEHICLE

Gordon P. Rathbun, Bedford, Ohio

Application March 18, 1944, Serial No. 112,956

Term of patent 3½ years

(Cl. D34—15)

To all whom it may concern:

Be it known that I, Gordon P. Rathbun, a citizen of the United States, residing at Bedford, in the county of Cuyahoga, and State of Ohio, have invented a new, original, and ornamental Design for a Toy Vehicle, of which the following is a specification, reference being had to the accompanying drawing, forming part thereof, wherein:

I claim:

The ornamental design for a toy vehicle, substantially as shown.

GORDON P. RATHBUN.
